SOLE FOR FOOTWEAR

Marion S. Mistarz, 105 N. Marion St.,
Oak Park, Ill. 60301

Filed Oct. 14, 1968, Ser. No. 13,969

Term of patent 14 years

Int. Cl. D2—04

U.S. Cl. D2—320

I claim:

The ornamental design for a sole for footwear, substantially as shown.
